[57] CLAIM

The ornamental design for a floor lamp, as shown and described.

DESCRIPTION

FIG. 1 is a front elevational view of a floor lamp constructed in accordance with the invention;

FIG. 2 is a rear elevational view of the floor lamp of FIG. 1;
FIG. 3 is a right side elevational view of the floor lamp of FIG. 1;

FIG. 4 is a left side elevational view of the floor lamp of FIG. 1;

FIG. 5 is a top plan view of the floor lamp of FIG. 1; and,
FIG. 6 is a bottom plan view of the floor lamp of FIG. 1.
The stippling shown in the Figures is for shading purposes only, and does not form a part of the claimed design. The broken lines showing the glass lampshade are for illustrative purposes only and form no part of the claimed design.
